(57) **CLAIM**

I claim the ornamental design for a soap bottle, as shown and described.

DESCRIPTION

FIG. 1 is a perspective view of the soap bottle;

FIG. 2 is a front elevational view thereof;

FIG. 3 is a rear elevational view thereof;

FIG. 4 is a right side elevational view thereof, the left side elevational view being identical; and,

FIG. 5 is a top plan view thereof.
